UNITED STATES PATENT OFFICE.

CHARLES J. KINDEL, OF ST. LOUIS, MISSOURI.

DAVENPORT.

No. 880,221.

Specification of Letters Patent.

Patented Feb. 25, 1908.

Application filed March 29, 1906. Serial No. 308,749.

To all whom it may concern:

Be it known that I, CHARLES J. KINDEL, a citizen of the United States, residing at St. Louis, State of Missouri, have invented a new and useful Improvement in Davenports, of which the following is a specification.

This invention relates to an improvement in folding beds and particularly to that class of folding beds known as davenports.

10 One object of the invention is to construct a bed of this sort in a manner such that the back of the davenport, when in settee form, may be suitably supported in substantially vertical position and may be brought forward 15 into horizontal position in front of the seat to form with said seat a comfortable bed, and when in that position be supported in part by the same means which sustain it in vertical position.

20 Another object of the invention is to combine with the seat and back a pad, which shall serve as a cushion for the back when the davenport is in settee form and a bed pad or mattress for the davenport, when in bed 25 form, and which shall automatically assume the positions wherein to perform both said functions when the davenport is changed from one of its forms to the other.

With these objects in view the invention 30 consists in the formation and combination of parts substantially as hereinafter described and claimed.

In the accompanying drawings, which form a part of this specification, Figure 1 35 represents in end elevation a davenport in settee form embodying my invention and Fig. 2 represents an end elevation of said davenport in bed form.

The seat of the davenport may be of any 40 desired form and construction. It is here represented at 3 as consisting of a simple lounge or divan, upholstered with a cushion 4, beneath which any suitable form of spring or other resilient support may be located.

45 The back of the davenport consists of a frame 5, upon the face of which is mounted a pad consisting of sections 6 and 7. The section 6 consists of a cushion supported upon any form of suitable springs or other 50 resilient supports well known to upholsterers, while the section 7 is preferably in the form of a tufted pad, the outer surface of which corresponds with that of the seat, while its rear surface corresponds with the outer face 55 of section 6, both of which surfaces are preferably covered with ticking. The sections

6 and 7 are hinged together in any suitable way at their upper edges and the section 7 is also preferably hinged to the seat cushion as indicated at 8, though this hinge, if desired, may be omitted, or if desired, pad 7 can be extended and tied in any suitable manner to the frame 3.

The back may be connected to the seat in any suitable manner which will permit it to be brought forward into horizontal position in front of the seat. One form of such support is herein illustrated and consists of links 9 pivoted to the seat at either end thereof and to either end of the back at the lower edge thereof. Integral with the links 9 there are preferably formed legs 10 against which stops 11 on the ends of the back rest, thereby sustaining the back in its vertical position.

75 With a davenport thus constructed it is readily changed from settee form into bed form by taking hold of the upper edge of the back and pulling the back forward. Said back will rotate about the pivots 12 and the 80 links 9 will rotate about the pivots 13, the pad 7 and said links serving to guide or direct the back into horizontal position in front of the seat as said back is pulled forward. The legs 10 then support the outer edge of 85 the back, while the inner edge is held to the seat by the connection of section 7 of the pad with section 6 thereof, and by the links 9. A ledge 14 may be provided upon the front edge of the seat to serve as a support for the 90 inner edge of the back when in bed form.

95 It will be seen that in a davenport constructed as shown and described the bed surface of the pad, consisting of sections 6 and 7, is entirely hidden from view when the davenport is in settee form, and with section 7 hinged to the seat, said pad is automatically displayed in the act of shifting the back over into horizontal position in front of the seat and automatically folded in converting the 100 davenport again into settee form. It will also be observed that because the sections 6 and 7 are hinged together a smooth continuous bed surface is produced without any objectionable joint between the two portions 105 thereof.

The invention claimed is:—

1. In a davenport, wherein the back is adapted to be brought forward into horizontal position in front of the seat, the combination with said back of a bed pad hinged to the upper edge thereof and hanging in front

of the same and adapted to cover the seat when the back is placed in said horizontal position.

2. In a davenport, wherein the back is adapted to be brought forward into horizontal position in front of the seat, the combination with said back of a bed pad hinged to the front side upper edge of the back and to the seat and adapted to be displayed when the back is placed in said horizontal position.

3. In a folding bed, the combination with a main portion and a folding portion, of a pad on said main portion, a second pad on said folding portion, and a third pad secured to one edge of said second-named pad and to a point intermediate of the edges of said first pad.

4. In a davenport, wherein the back is adapted to be brought forward into horizontal position in front of the seat, the combination with said back of a bed-surfaced cushion on the face of the back, a pad hinged to said cushion at its upper edge and having a bed surface on its inner side and a cushion surface on its outer side whereby, when the back is placed in said horizontal position, the cushion surface will lie upon the seat and said two bed surfaces will form a continuous bed surface for the davenport bed.

5. In a davenport, the combination with the seat, of a back, links at either end of the davenport connecting the back to the seat

and adapted to direct it into horizontal position in front of the seat, and a pad hinged to the upper edge of the back and having a bed surface on its inner side and a cushion surface on its outer side whereby, when the back is placed in said horizontal position, the bed surface will be displayed over the seat.

6. The combination with the seat, of a back, links at either end of the davenport connecting the back to the seat and adapted to direct it into horizontal position in front of the seat, and a pad hinged to the upper edge of the back and to the seat and adapted to be displayed upon the seat when the back is placed in said horizontal position.

7. In a davenport bed, a seat section, a movable back section adapted to be moved into horizontal alinement with said seat section and a covering section in front of said back section connected to said back section and adapted to be moved to a position over said seat section when said back section is moved into alinement with said seat section, substantially as set forth.

In testimony whereof I have signed my name to this specification in the presence of two subscribing witnesses.

CHARLES J. KINDEL.
